(57) **CLAIM**

I claim the ornamental design for a sleeve for a frozen confection, as shown and described.

DESCRIPTION

FIG. 1 is a front elevational view of a sleeve for a frozen confection according to an embodiment of the present invention.

FIG. 2 is a front perspective view of the sleeve for a frozen confection of FIG. 1.

FIG. 3 is a second front elevational view of the sleeve for a frozen confection of FIG. 1, the view from the rear being a mirror image thereof.

FIG. 4 is a top plan view of the sleeve for a frozen confection of FIG. 1, the view from the bottom being a mirror image thereof; and,

FIG. 5 is left side view of the sleeve for a frozen confection of FIG. 1, the view from the right side being a mirror image thereof.

The broken lines represent environmental elements only and form no part of the claimed design.
